UNITED STATES PATENT OFFICE.

RICHARD FINN, OF CHICAGO, ILLINOIS.

SUPPLY AND WASTE VALVE.

SPECIFICATION forming part of Letters Patent No. 396,151, dated January 15, 1889.

Application filed February 16, 1888. Serial No. 264,221. (No model.)

To all whom it may concern:

Be it known that I, RICHARD FINN, residing at Chicago, in the county of Cook and State of Illinois, and a citizen of the United States, have invented a new and useful Improvement in Supply and Waste Valves, of which the following is a specification, reference being had to the accompanying drawings, in which—

10 Figure 1 is a sectional elevation showing the supply-valve open and the waste-valve closed. Fig. 2 is a sectional elevation with the upper end of the case and the pull-rod broken off, showing the supply-valve closed and the waste-valve open. Fig. 3 is a detail in section of the supply and waste valves.

15 The object of this invention is to construct a supply and waste valve for use with water-closets or in other places where it is desired, to have a supply when required, and after the supply is shut off have the waste run off, and for such purpose it is desirable that the waste and supply shall work simultaneously—that is, when the supply is open the waste must be

20 closed, and when the supply is closed the waste is open; and to attain this object of a simultaneous closing and opening of the supply and waste is the main object of this invention; and its nature consists in the several 25 parts and combinations of parts hereinafter described, and pointed out in the claim.

In the drawings, A represents a shell or case of a cylindrical shape in cross-section, as shown, and having one end open and the other closed.

30 B is a shell or case corresponding in shape to that of the shell or case A, and screw-threaded or otherwise connected with the case A, and, as shown, the case B has a flange, a, on its exterior, to coact with the end of the case A and form a tight joint at the juncture of the two cases, and the lower end of the case B is provided with ears or a flange, b, by means of which it is attached to a suitable 40 support. The object in making the case or shell in two parts is to enable access to be readily had to the interior for replacing the valve or making other repairs.

C is a nipple screw-threaded on its exterior 45 for attachment to a water-supply pipe and having an opening or passage, c, leading to the chamber of the case A B.

D is the receiving-chamber of the case A B, in which chamber is a diaphragm or wall, d, standing inclined and having at its center an opening, e, for the passage of the water-supply.

E is a chamber in the case A, above the diaphragm d, into which the water-supply passes when the supply-valve is open.

F is a nipple screw-threaded on its exterior for the attachment of a pipe leading to the place to be supplied with water and having a passage, f, which forms an outlet from the chamber E.

G is the supply-valve, of rubber or other suitable material, and of the shape shown or other shape by which the opening or passage e can be closed.

H is a tube, on which is secured the ball-valve G, between a head, h, of the tube and a washer, g, and, as shown, the lower end of the tube H is screw-threaded to receive a continuation, H', of the tube H, which continuation passes through a packing-box, h', and enters the waste-chamber in the case B.

I is a ball-valve, of rubber or other suitable material, and of the form shown or other form that will properly seat on the head h and close the passage through the tube H.

J is a cage or basket inclosing the valve I, and screw-threaded or otherwise secured at its lower end to the head h, and having in its side wall openings i, through which the waste water can pass, and having also on its upper end a cap or cover, j, which may be formed with the cage J, or be a separate piece screw-threaded or otherwise secured to the cage.

K is a stem the lower end of which passes through the cover j and enters the cage J, and, as shown, this stem has a screw-threaded smaller portion, k, to receive the valve I and allow the valve to be adjusted to seat properly on the head h.

L is a lever, to which is attached by a pin or pivot, l, an eye, k', on a head, K', attached to the upper end of the stem K.

M is an arm or bracket, to which is pivoted the end of the lever L by a pin or pivot, m.

N is a neck on the upper end of the case A, around which is placed the ring carrying the arm or bracket M.

O is a cap screw-threaded onto the neck N, and holding the ring of the bracket M in

place, and through which passes the stem K, suitable packing being provided to make a tight fit.

5 P is a weight on the lever L, by which the stem K is forced down.

Q is a chain or rope attached to the outer end of the lever L, and by means of which the lever is raised to lift the stem K.

10 R is the waste-chamber in the case B, formed by a partition, n, and a wall, o, and into which the waste-tube H H' leads.

15 S is a nipple for the attachment of the waste-pipe, and having a passage leading into the chamber R.

20 15 The stem K is passed through the cover j of the cage J, and to its end k is attached the valve I, and the lower end of the cage J is screwed or otherwise secured onto the head h of the tube H, to have the valve I seat on the head h of the tube H when the valve is down.

25 The ball-valve G is placed on the tube H and the washer g slipped on the tube, and the tube H and its continuation H' are screwed together, connecting the stem K, cage J, valve I, valve G, and tube H H' together. The tube H' is passed through the stuffing-box h' into the chamber R, and the stem K is passed through the cover O and the two sections A B of the case screwed or otherwise secured 30 together. The head K' is attached to the lever L, having thereon the weight P, and attached to the arm or bracket M, and the lever is connected with the chain or rope Q, and the case attached to its support by the ears b or 35 otherwise, when the device is ready for use by connecting the nipple C to the supply-pipe for the water and the nipple F to the pipe leading to the place to be supplied and attaching a waste-pipe to the nipple S.

40 40 The valves G and I are adjusted in such relation to each other that when the valve I is forced down by the dropping of the lever L through the stem K it will close the passage through the tube H H' and at the same 45 time open the valve G, and when the valve I is raised by drawing on the chain or rope Q to lift the lever L and raise the stem K such action will raise the valve G and close the passage e between the chambers D and E.

50 50 In use, to open the supply the chain or rope Q is released, allowing the weight P to drop and throw down the lever L, forcing down the stem K and valve I, closing the passage through the tube H H' and opening the valve 55 G, so that water can enter through the pas-

sage e into the chamber D and pass through the opening e into the chamber E, and thence through the passage f to the place to be supplied, and when the required supply is had the lever L is raised, raising the valve I 60 through the stem K, and at the same time through the cage J, raising the valve G and shutting off the supply, and when the valve G is closed the valve I is open, allowing the waste to pass into the chamber E and thence 65 through the opening i of the cage J into the tube H to enter the waste-chamber R and pass therefrom.

It will be seen that when the valve G is open, as in Fig. 1, to allow a supply, the valve 70 I is closed down to shut off the escape of the waste, and when the valve G is closed, as in Fig. 2, to shut off the supply, the valve I is open, allowing the waste to escape through the tube H H', the result being that the movement of the valve I to close the waste will 75 open the supply-valve, and the movement of the valve I to open the waste will close the supply-valve, so that this valve I controls in effect both the supply and waste by operating 80 the supply-valve.

The tube H H' is made in two parts, so that the ball-valve G can be readily removed to be replaced by a new valve, and the cage is detachably attached to the ball-valve tube H, 85 so that it can be removed to replace the valve I whenever required.

The tube H' passes through the stuffing-box with sufficient friction to prevent the valve G from falling away from the valve I when 90 the parts are as shown in Fig. 2, or the end of the tube H' can be made to strike the bottom of the chamber R and hold the valve, or a stop can be placed on the tube to strike the stuffing-box. 95

What I claim as new, and desire to secure by Letters Patent, is—

In a supply and waste valve, a waste-tube, H, carrying a supply-valve seating upward, and a cage, J, above the supply-valve, in combination with a valve-stem, K, carrying a waste-valve, I, located in the cage J and seating downward to close the waste-tube H for simultaneously opening and closing the valves, substantially as specified.

RICHARD FINN.
